Fig. 7

Fig. 8

FIG. 1 is a front perspective view of a support bracket for electrical components showing my new design;

FIG. 2 is a top plan view of the bracket;

FIG. 3 is a front elevational view of the bracket;

FIG. 4 is a rear elevational view of the bracket;

FIG. 5 is a bottom plan view of the bracket;

FIG. 6 is a side elevational view of the bracket looking from the left-hand side in the direction of the arrows 6 in FIG. 5, the side elevational view from the right-hand side being identical;

FIG. 7 is a central sectional view through the bracket taken substantially along line 7—7 of FIG. 5; and

FIG. 8 is a transverse sectional view through the bracket outboard of the center and taken substantially along line 8—8 of FIG. 5.

I claim:

The ornamental design for a support bracket for electrical components, substantially as shown.
